UNITED STATES PATENT OFFICE

159,938

BABY'S BOTTLEHOLDER

Dorothy Mary Suich, Altadena, Calif.

Application February 14, 1949, Serial No. 839

Term of patent 14 years

(Cl. D83—8)

To all whom it may concern:

Be it known that I, Dorothy Mary Suich, a citizen of the United States of America, residing at Altadena, in the county of Los Angeles and State of California, have invented a new, original, and ornamental Design for a Baby's Bottleholder, of which the following is a specification, reference being had to the accompanying drawing, forming part thereof.

Fig. 1 is a perspective view looking diagonally downwardly at the baby's bottleholder, showing my new design;

Fig. 2 is a side elevation of the bottleholder shown in Fig. 1; and

Fig. 3 is a view of the bottom of the bottleholder as shown in Fig. 1.

The dominant features of my design reside in the portions shown in full lines.

I claim:

The ornamental design for a baby's bottleholder, substantially as shown and described.

DOROTHY MARY SUICH.
